UNITED STATES PATENT OFFICE.

JOHN W. SHROCK, OF AKRON, OHIO.

TRACTION ATTACHMENT FOR WHEELS.

Application filed June 25, 1920. Serial No. 391,670.

To all whom it may concern:

Be it known that I, JOHN W. SHROCK, a citizen of the United States, residing at Akron, in the county of Summit and State 5 of Ohio, have invented new and useful Improvements in Traction Attachments for Wheels, of which the following is a specification.

This invention relates to a new and improved device which is adapted to be attached to a drive wheel of a self-propelled vehicle to increase the traction thereof.

The invention has special reference to a device particularly adapted for use in extricating trucks and other vehicles from mud, deep sand and other places in which the drive wheels will freely spin and no traction can be secured.

The main object of the invention is to 20 provide a strong, durable, compact device of simple, economical construction, which may be easily and quickly attached to said wheels and which when so attached will increase the traction thereof so that the vehicle may 25 be driven through mud, soft earth or sand of such depth that it would be ordinarily impossible to drive a self-propelled vehicle therethrough.

The above and additional objects are 30 accomplished by the novel construction herein described and illustrated in the accompanying drawings, it being understood that the invention is capable of various adaptations and that changes and modifications may be 35 resorted to which come within the scope of the claim hereunto appended.

In the drawings in which similar numerals of reference are employed to designate corresponding parts throughout the 40 several views, and in which—

Figure 1 is a perspective view of a device constructed in accordance with this invention.

Figure 2 is an end view of said device 45 showing the same as applied to a wheel, a portion of the wheel being shown in side elevation.

Figure 3 is a sectional view taken as indicated by the line 3—3 of Figure 2.

Proceeding now with a detailed description, a device constructed in accordance with this invention comprises a box like structure provided with a bottom or base plate 5, end walls 6 and 7 and side walls 8 50 and 9. The base plate 5 is curved laterally to provide an arcuate surface which con-

forms with the circumferential outline of the tire 10 on which it is to be used. The base of each side wall 8 and 9 is positioned inwardly from and in parallel, spaced relation to the lateral sides of the plate 5 and each of said side walls extends upwardly from the said base plate. The portion of the base plate 5 projecting beyond the base of the side wall 8 forms the ledge 11 and likewise, the portion of the said base plate projecting beyond the base of the wall 9 forms the ledge 12. The end walls extend upwardly and outwardly from the ends of the base plate 5 and are laterally arched to 70 provide an outwardly projecting bulge. It will be seen that the end walls 6 and 7 diverge outwardly and are considerably lower than the side walls 8 and 9 and are integral with the side walls and the bottom 5. A 75 centrally positioned opening 14 is cut or otherwise formed at each end of the device, the same being positioned on the line of juncture between the end walls and the base plate 5 so as to extend into both the said 80 base plate and the end wall. A centrally positioned strengthening web or partition 13 extends laterally across the device from the side 8 to the side 9, the same being integral with said side walls and integral with 85 the bottom 5. Each end of said partition 13 is of approximately the same height as the side wall 8 and 9, the said partition being curved downwardly from each side wall to provide a relatively low central portion 90 as clearly shown in Figure 1. A strengthening bracket 15 extends upwardly from the ledge 11 adjacent each end of the device. The said strengthening brackets being integral with the base plate and the side wall 95 8. Similar brackets 15 extend upwardly from the ledge 12 and are integral with the side 9.

In use, the device is placed laterally across a tire as shown in Figures 2 and 3, a 100 chain 16 is passed through one of the openings 14 over the central portion of the partition 13 and through the other opening 14, the ends of the chain being secured together, underneath the felly 17 of the wheel. The 105 device is particularly adapted to be placed in the tool box of a motor truck or similar vehicle so that should the vehicle become stalled in deep sand or mud, the device may be easily and quickly attached as above set 110 forth, whereupon the rotation of the wheel will cause the side walls 8 and 9 to engage

the sand or mud and permit the vehicle to be driven under its own power therefrom.

While I have shown and described a device which is adapted to be applied to an ordinary truck tire, it is to be understood that the shape of the base plate may be varied to adapt it to all styles of tires.

Having thus described my invention what I claim as new and desire to secure by Letters-Patent is:—

In a device of the class described, an integral box-like structure, comprising a bottom plate, arched laterally to conform to the

circumferential outline of a wheel; parallel side walls, outwardly bulged, relatively low end walls; an opening in each end wall a centrally positioned, laterally extending, strengthening partition; said bottom plate extending outwardly beyond said side walls, each of said openings being positioned at the base of an end wall so as to extend into both the end wall and base plate, substantially as herein set forth.

In testimony whereof I have hereunto set my hand.

JOHN W. SHROCK.
